UNITED STATES PATENT OFFICE.

GEORGE F. SUMNER AND EUGENE MOSER, OF MOUNT CLEMENS, MICHIGAN.

BOX-FASTENER.

SPECIFICATION forming part of Letters Patent No. 373,758, dated November 22, 1887.

Application filed April 13, 1887. Serial No. 234,663. (No model.)

To all whom it may concern:

Be it known that we, GEORGE F. SUMNER and EUGENE MOSER, of Mount Clemens, county of Macomb, State of Michigan, have invented 5 a new and useful Improvement in Box-Fasteners; and we declare the following to be a full, clear, and exact description of the same, such as will enable others skilled in the art to which it pertains to make and use it, 10 reference being had to the accompanying drawings, which form a part of this specification.

Our invention consists of the combinations 15 of devices and appliances hereinafter specified, and more particularly pointed out in the claims.

In the drawings, Figure 1 is a perspective view of a shipping-box embodying our invention. Fig. 2 is a longitudinal section of the same. Fig. 3 is a separate view of the retaining-clamp. Fig. 4 is a variation in which the clamp is all made in a single piece. Fig. 5 20 illustrates different methods for temporarily holding the hinged clamp in place for shipment. Fig. 6 illustrates a variation.

25 Goods—such as bottles, eggs, and the like—are shipped in large quantities in packages, and provision is frequently made for a certain amount allowed to the purchaser upon the return of the package. In use, however, by 30 the ordinary method of nailing the top boards or cover to the box, it usually transpires, by the driving of the nails or the opening of the box, that the boards through which the nails are driven and those into which they are set are 35 split and damaged to such an extent that the value of the package is greatly impaired.

It is the object of this invention to provide 40 means for clamping the top or covering boards into place without the use of any nails, and yet admit of the ready release of the said clamp or clamps in order to open the box.

In carrying out our invention, A represents 45 an ordinary box.

B B B represent the covering boards, which 50 constitute the top of the box.

C represents our improved clamps for holding 55 the boards in place. These clamps consist of a strap, c, adapted to extend over the tops of the boards, and with ears projecting down upon the side and hinged by a screw or nail at c'. An angle-plate, c², is riveted to the strap or made to constitute a part of the same,

and projects down over the ends of the boards B against the face of the boards at the ends of the box.

55

c³ represents fastenings.

There may be permanent fastenings for the clamp located at one end of the box and temporary fastenings for the clamp located at the opposite end of the box. Such temporary fast- 60 enings are shown in Fig. 5. It may be in the nature of a screw-hook or key, c⁴, or of a removable screw, c⁵, or of any other convenient form whereby the clamp can be easily released, so as to permit of its being turned down, as 65 shown in Fig. 2, so as to release the boards B. That clamp which is stationary at the other end of the box may be so fixed by two or more nails or screws passing through the strap c, as shown in Fig. 1, or it may be fastened both at 70 this point on the strap and at the end of the box through the depending flange of the angle-plate. So, also, if desired, the angle-plate on this permanent clamp need not project down any farther than sufficient to prevent endwise 75 shifting of the boards B. So, also, at the temporary clamp designed to be turned down about the pivots c', the temporary fastenings might be at the end portions of the strap, as shown in Fig. 6, in which the screw D is employed, 80 grooved or flattened at d, to permit it to enter the slot d' in the strap, after which a quarter-turn of the screw will fasten the strap securely.

It is apparent that a package of this character may be used time and again without any 85 injury either to the box proper or its covering-boards.

This appliance is adapted for use with ordinary loose box-boards, such as are usually employed for box-covers, and without the necessity of fastening the boards together. We would also have it understood that a box may have but one of these hinged clamps C, the other one being in the nature of a permanent clamp or strap, with a depending angle-piece 95 to engage the ends of the boards.

What we claim is—

1. The combination, with a packing-box, of a clamp, C, having ears c c, pivoted at c' c', and an angle-plate, c², provided with elongated 100 slots, and the screw-hooks c⁴ c⁴, for securing said angle-plate to the box, substantially as described.
2. The combination, with a packing-box, of

a clamp having ears c and angle-plates c^2 ,
said clamp being permanently secured to one
end of the box, a similar clamp pivoted to the
other end of the box and provided with elong-
ated slots formed in its angle-plate, and the
screw-hooks c^4 c^4 , for engaging said slots and
securing the pivoted clamp to the box, sub-
stantially as described.

In testimony whereof we sign this specifica-
tion in the presence of two witnesses.

GEORGE F. SUMNER.
EUGENE MOSER.
